LIQUID PRESSURE REMOTE CONTROL SYSTEM, MORE PARTICULARLY FOR OPERATING SOOT BLOWERS OF BOILERS AND THE LIKE

Frederick Sydney Eves, London, England, assignor to Automotive Products Company Limited, London, England

Application December 7, 1940, Serial No. 369,104
In Great Britain February 16, 1940

8 Claims. (Cl. 121—157)

This invention relates to liquid pressure remote control systems, more particularly for operating soot blowers of boilers and the like.

It is the primary object of the present invention to provide an improved form and construction of liquid pressure remote control system of the form in which a double-acting piston and cylinder unit is arranged in conjunction with trip valves for the purpose of securing automatic reversal of the direction of movement and thus enabling the unit to operate with a reciprocatory motion when fed with pressure liquid. In particular the invention seeks to provide an improved arrangement for the trip valves whereby the latter are adapted to operate, at a distance, the means which are used for making the necessary reversals in the supply of pressure liquid. The invention is thus especially suitable for hydraulically actuated soot blowers of boilers and the like, as it enables the more intricate reversing valve mechanism and its associated parts to be positioned well away from the heat of the boiler or equivalent.

In a liquid pressure remote control system in which a double-acting piston and cylinder unit is connected with a reversing valve device by a pair of interchangeable supply and return pipe lines, the present invention is characterised by the fact that said reversing valve device is actuated by pressure liquid fed thereto through a shunt pipe line under the control of the unit.

Further, in a liquid pressure remote control system in which a double-acting piston and cylinder unit is fed with pressure liquid from a source through the medium of a reversing valve device connected with said unit by a pair of interchangeable flow and return pipe lines, according to the invention the piston and cylinder unit is adapted to operate a trip valve at the end of each stroke, thereby diverting its own feed of pressure liquid into a shunt pipe line and thence to an auxiliary motor device which changes over the reversing valve device.

Thus there is provided according to the invention a liquid pressure remote control system having in combination with a double-acting piston and cylinder unit, a reversing valve device operated by a double-acting auxiliary motor, which latter is fed with pressure liquid through the medium of a trip valve device actuated by the said double-acting unit as the end of each stroke is reached, so that the piston and cylinder unit is caused to oscillate continuously so long as the supply of pressure liquid to the unit is maintained.

Further, there is provided in conjunction with a liquid pressure remote control system, a reversing valve device which is connected with a source of pressure liquid and a reservoir, connected with a double-acting piston and cylinder unit by a pair of interchangeable flow and return pipe lines and is also connected by a shunt pipe line with a trip valve device actuated by the piston and cylinder unit, said reversing valve device comprising a double-acting motor, an auxiliary reversing valve interposed between the shunt pipe line and said auxiliary motor, and a main reversing valve arranged to change over the main flow and return pipe lines to the piston and cylinder unit, the arrangement being such that when the piston and cylinder unit reaches the end of its stroke it operates the trip valve device which diverts the supply of pressure liquid into the shunt pipe line and thence to the auxiliary motor unit, thus changing over the main reversing valve and at the same time changing over the auxiliary reversing valve so that the auxiliary motor is actuated in the opposite direction the next time pressure liquid is diverted to the shunt pipe line.

Preferably the reversing valve device comprises a body formed with a pair of bores, one of which contains a piston constituting the movable element of the auxiliary motor, while the other contains a piston valve member acting as two individual reversing valves, one being interposed between the pressure supply and the flow and return pipe lines of the piston and cylinder unit, which is double acting, and the other being interposed between the shunt pipe line and the working spaces of the auxiliary motor. The piston valve member may be mechanically interconnected with the auxiliary motor by a "snap-over" mechanism adapted to move the piston valve member rapidly from one extreme position to the other as the piston of the auxiliary motor executes its stroke, said "snap-over" mechanism conveniently comprising an arm provided with a spring arranged to pass a dead centre position, the said member being coupled with the piston valve member and the motor piston individually by lost motion connections.

In the piston and cylinder unit each of the trip valves may be urged towards its closed position by the pressure liquid which is being fed to the unit, and the opening force which is exerted upon said valve by the movable member of the piston and cylinder unit at the end of the stroke of the latter, may be transmitted through a resilient member adapted to store energy, which latter

is utilised to open the trip valve rapidly immediately the fluid supply pressure is overcome. In cases where the unit comprises a cylinder and movable piston the trip valves may be fitted into the ends of said cylinder so as to be opened directly by the piston as the latter reaches the end of each stroke. Thus in one arrangement the unit comprises a cylinder, a hollow double-acting piston slideable therein, and a tubular stem fixed to one cylinder end and arranged to extend in a liquid-tight manner into the open end of the piston, the arrangement being such that the piston is retracted at a relatively rapid rate by feeding pressure liquid into the piston through the tubular stem, the forward or power stroke of the piston being effected by feeding pressure liquid into the opposite end of the cylinder.

During the retracting stroke of the piston a part of the liquid rejected from the said opposite end of the cylinder may be permitted to flow into the annular space surrounding the tubular stem within the cylinder, the trip valve at the "stem" end of the cylinder conveniently being opened by an annular member which surrounds the stem and is mounted upon the piston but urged away therefrom by means of a coiled compression spring, while the trip valve at the said opposite end of the cylinder is actuated by a spring-pressed plunger member mounted centrally in the corresponding end of the piston.

If desired a pair of trip valves corresponding respectively to the opposite ends of the stroke of the unit may be connected with a single shunt pipe line, each through the medium of a non-return valve adapted to prevent the pressure liquid flowing directly from one trip valve to the other, although, of course, said liquid can flow from either trip valve into the shunt pipe line.

A pair of trip valves, each arranged to terminate movement of the unit in one direction, may be interconnected with the movable member thereof through mechanism adapted to modify the length of stroke executed by the said movable member, the unit conveniently being arranged to operate a cam device by which the trip valves are actuated and which moves with a reversing motion corresponding to the strokes of the unit, while a follower device is caused to follow a continuous circuit uni-directionally. The cam device may thus comprise a drum formed in its outer curved surface with a groove including a continuous circuit which is traversed uni-directionally by a follower member, said circuit having terminal portions, the end parts of which bring about the operation of one or other of the trip valves, thus reversing the motion of the movable member of the piston and cylinder unit and also of the cam.

As a further aspect of the invention a soot blower installation for a boiler furnace or the like is provided having a blower nozzle operated by a liquid pressure remote control system as above defined. Thus there may be interposed between the unit and the blower nozzle a driving connection comprising a pair of members which normally transmit, from one to the other, the force generated by the piston and cylinder unit, and which are arranged so that, when the transmitted force exceeds a predetermined value, relative movement of the members takes place and actuates a valve to stop the flow of pressure liquid into the piston and cylinder unit, one of the force transmitting members conveniently having a longitudinally extending push rod which is actuated by the other member to oper-

ate a valve for stopping the flow of pressure liquid to the piston and cylinder unit, said push rod, or a member serving to actuate it, being engaged with a recess in the said other member when the device is in its normal, force-transmitting state.

The invention is illustrated by way of example in the accompanying drawings, in which:

Figure 1 is a diagram showing the arrangement of a simple form of remote control system, the reversing valve device being drawn as a sectional elevation and the piston and cylinder unit being of elementary form;

Figure 2 is a sectional elevation of a piston and cylinder unit incorporating trip valves and arranged to provide a quick return motion;

Figure 3 is a fragmentary sectional elevation of a soot blower device of the retractable type and including an automatic cut-out device;

Figure 4 is a fragmentary sectional elevation drawn to an enlarged scale and taken mainly on the line 4-4 of Figure 3, although the left-hand trip valve is shown as a section taken on the line 4a-4a;

Figure 5 is a diagram representing a development of the outer curved surface of the control cam shown in Figures 3 and 4; and

Figure 6 is a fragmentary perspective view of a part of the control cam.

The remote control system which is partly indicated in diagrammatic form in Figure 1 comprises a continuously running pump 10, which is replenished by a reservoir 11 and normally delivers pressure liquid into a pressure supply pipe 12 leading to a reversing valve device indicated generally at 13. From the latter a return pipe 14 leads back to the reservoir 11 and pump 10. From the reversing valve device 13 a pair of interchangeable flow and return pipe lines 15 and 16 lead respectively to the working spaces 17 and 18 of a double-acting piston and cylinder unit indicated generally at 19. This unit has a pair of cylinders 20 and 21 fitted with end caps 22 and 23 respectively, and they contain a pair of pistons 24 and 25 connected together by a rack bar 26. The teeth of the latter are in permanent mesh with a pinion 27 carried upon a transverse shaft 28, said shaft thus being caused to rotate first in one direction and then in the other as the piston assembly 24, 25, 26 reciprocates. The cylinder caps 22 and 23 are fitted with spherical trip valve members 29 and 30, each of which is urged on to its seat by a coiled compression spring 31, while it is adapted to be pushed off its seat by a longitudinally slidable pin 32 or 33. These pins 32 and 33 are arranged to be operated by the corresponding pistons 24 and 25 as each of said pistons reaches the end of its retracting stroke. The trip valve member 29 is also normally urged on to its seating by any pressure existing in the flow or return pipe line 16, to which it is connected by a pipe 16a, while the trip valve member 30 is similarly connected by a pipe 15a with the flow or return pipe line 15. When either of the trip

valve members 29 or 30 is open, liquid is able to flow past the corresponding one of a pair of non-return valves 34 and 35, which are joined by connections 36 and 37 with a shunt pipe line 38 leading back to the reversing valve device 13. The non-return valves 34 and 35, of course, prevent pressure liquid from one of the trip valves 29 and 30 from flowing back into the other trip valve.

The reversing valve device as shown in Figure 1 comprises a body 39, which is formed with a pair of mutually parallel bores 40 and 41,

the former of which is arranged to act as the cylinder of an auxiliary double-acting hydraulic motor. A piston 42 fitted securely to a piston rod 43 has packing cups 44 and 45 and is slidably mounted in the bore 41, the end portions of said piston rod 43 being arranged to pass slidably through bushes 46 and 47 fitted with packing cups 48 and 49 respectively. Thus the interior of the bore 41 is divided into two working spaces 50 and 51 communicating with passages 52 and 53 through which working liquid passes to and from the auxiliary motor. At one end the piston rod 43 is fitted with an adjustable forked member 54 carrying the pivot 55 of a link 56, the opposite end of said link being formed with a slot 57 engaged by a pin 58 mounted upon an arm 59, which latter is pivotally mounted at 60 upon a fixed support. A coiled tension spring 61, having its lower end fastened pivotally at 62 to a fixed support, is arranged to extend upwardly and is fastened at its opposite end to the upper extremity of the arm 59, the spring 61 thus being arranged to pass a dead centre position as the arm 59 moves in a counter-clockwise direction, as seen in Figure 1. This causes the arm 59 to have a "snap-over" action, for as the piston 42 moves towards the left the pin 58 is first engaged by the right-hand end of the slot 57 and thereafter the arm 59 is propelled forwardly, said arm eventually reaching and passing its vertical dead centre position, after which the spring 61 takes charge, thus drawing the arm 59 rapidly towards the left as far as is permitted by the lost motion device comprising the slot 57 and pin 58. This motion is utilised to change over a piston valve member 63, which fits slidably within the bore 49 and has its end parts 64 and 65 passing slidably through bushes 66 and 67, packing cups 68 and 69 being provided to prevent leakage of liquid. The piston valve member 63 is formed with a longitudinal bore 70, which is sealed at its ends by screw-threaded members 71 and 72. The screw-threaded member 71 is bifurcated at 73 to receive a link 74 which is pivoted at 75 and which has its opposite end formed with a slot 76 constituting a lost motion connection in conjunction with a pin 77 carried by the arm 59. The length of the slot 76 is arranged so that the pin 77 moves freely along it until the arm 59 is just about to reach the end of its angular movement, the pin 77 at this instant engaging with the end of the slot 76 so that the final movement of the arm 59, which is a rapid movement on account of the spring 61, causes the piston valve member 63 to be swiftly slid along to its opposite position.

The bore 70 within the piston valve member 63 is at all times in communication with the reservoir 11 on account of a port 78, to which the return pipe line 14 is connected, and which leads into an annular groove 79 connected with the bore 70 by radial passages 80. In a similar way the main supply pipe 12 is in permanent communication with an annular groove 81 in the piston valve member 63 by way of a port 82, and said groove 81 is adapted to place this port into communication either with a port 83 leading to the pipe line 16, as shown in Figure 1, or else with a port 84 leading to the pipe line 15, this last connection occurring, of course, when the piston valve member 63 is moved to the left. When the piston valve member 63 is in the position shown, the port 84 communicates with the reservoir so that the pipe 15 acts as a return, whereas when the valve member is moved to the

left, a relatively narrow annular groove 85 communicating with the bore 70 by radial passages comes into register with the port 83, thus placing the pipe line 16 into communication with the reservoir 11. The annular grooves 79, 81 and 85, acting in conjunction with the ports 78, 84, 82 and 83, thus constitute a reversing valve adapted to control the direction in which the piston and cylinder unit 19 is operated by the pressure liquid delivered by the pump 10.

The piston valve member 63 also acts as a reversing valve interposed between the shunt pipe line 38 and the passages 50 and 53 leading to the auxiliary motor 41, 42. Thus a port 86 connected with the shunt pipe line 38 communicates with an annular groove 87 adapted to place said port 86 either into communication with the passage 53, as shown, or into communication with the passage 52. The piston valve member 63 is also formed with a pair of narrow annular grooves 88 and 89, each of which has radial holes leading into the bore 70 and thence to the reservoir 11, the arrangement being such that when the piston valve member 63 is in the position shown, the passage 52 communicates with the reservoir 11, whereas when the valve member 63 is moved to the left, said passage 52 is in connection with the shunt pipe line 38, and the passage 53 then leads back to the reservoir 11 by way of the annular groove 89.

The reversing valve device 13, as shown in Figure 1, is arranged to enable the pistons 24 and 25 of the piston and cylinder unit 19 to reciprocate continuously so long as pressure liquid is being delivered by the pump 10. With the parts in the positions shown, pressure liquid passes from the supply pipe line 12 into the pipe line 16, and upon entering the working space 18 forces the piston 25 to the left, at the same time moving the rack bar 26 and the piston 24 so that the latter expels liquid from the working space 17 back to the reservoir by way of the pipe lines 15 and 14. As the piston 25 reaches the end of this retracting stroke it engages with the pin 32 and thus forces the trip valve 29 off its seating, so permitting pressure liquid from the pipe line 16 to flow through the non-return valve 34 and into the shunt pipe line 38. It will be seen that this pressure liquid flows through the passage 53 and, entering the working space 51, urges the piston 42 of the auxiliary motor to the left. As previously described, the piston valve member 63 remains unmoved until the arm 59 snaps over, at which instant the valve member 63 moves quickly to the left, thus cutting off the supply of pressure liquid to the pipe line 16 and transferring it to the pipe line 15. At the same time the valve member 63 changes over the shunt pipe line 38 to the passage 52 of the auxiliary motor. Pressure liquid is then fed from the pipe line 15 to the working space 17, thus moving the pistons 24 and 25 in the opposite direction until the trip valve 32 is opened by the engagement of the piston 25 with the pin 33. This action actuates the reversing valve device 13 so as to return the parts to their original positions and then movement of the pistons 24 and 25 towards the left begins once again. It will thus be seen that the reversing valve device 13, which enables the piston and cylinder unit 19 to reciprocate continuously, is not mechanically connected with the unit but is merely coupled thereto by the pipe lines 15, 16 and 38. These, of course, can be of any reasonable length and it is thus possible for the reversing valve device 13 to be placed well away from

the unit, this being an important advantage for soot blower installations, as the parts associated with the blower nozzles are liable to become rather hot.

A modified construction of piston and cylinder unit 19 is shown in Figure 2, and is particularly adapted for use in cases where the unit is intended to drive mechanism through the medium of a ratchet device, thus producing an intermittent uni-directional rotating movement, such as is desirable for driving a soot blower nozzle of the known non-retractable type. It is desirable in these circumstances for the "return" stroke of the unit to take place quickly and with a relatively small volume of pressure liquid, whereas the "forward" stroke has to develop the requisite power and can take place more slowly.

The unit comprises a central casting 90 formed with sleeves 91 and 92, into which the cylinders 20' and 21' are fitted. The central casting 90 contains a transverse shaft 28 carrying the pinion 27, which latter meshes as before with gear teeth 93 formed upon a rack bar 26'. A roller 131 mounted upon a pivot pin 132 secured to the central casting 90 is adapted to engage with the under surface 133 of the rack bar 26 so as to prevent the latter from bending on account of the load transmitted to the pinion 27. The piston 24' at one end of the rack bar 26' has an annular packing cup 94, while the piston 25' at the opposite end has a packing ring 95, which need only be capable of withstanding low fluid pressure. Secured firmly to the cylinder cap 23' is an axial tubular stem 96, which passes through an annular packing cup 97 fitted within the piston 25 by means of an annular nut 98. The stem 96 extends into a bore 99 formed in the rack bar 26' and thus produces an auxiliary working space 100 which is adapted to be fed with pressure liquid through the interior of the stem 96. The latter accommodates with clearance a metal tube 101 which is connected with a bleed plug 102 and is used merely for extracting air from the auxiliary working space 100 when the device is being charged with liquid.

The end cap 23' carries a pair of fittings 15b and 16b for connection to the pipe lines 15 and 16 respectively shown in Figure 1, said pipe lines, of course, leading to the reversing valve device 13. The fitting 16b has a passage 103, which passes direct to the interior of the stem 96 and thus leads into the auxiliary working space 100. A branch pipe connection 104 also connects the fitting 16b with a space within the other end cap 22', which space contains the trip valve member 29 and its spring 31, said trip valve member having, as before, a pin 32 by which it is adapted to be opened by the piston 24'. The fitting 15b has a pipe connection 105, by which pressure liquid is delivered through the opposite end cap 22' into the working space 17, while a branch connection 106 leads to the trip valve 30, which latter has a pin 33 adapted to open it against the closing force exerted by the corresponding spring 31. From the space containing the trip valve 30 a passageway 107, shown dotted, leads upward past a lightly loaded non-return valve member 108 and thence by a passage 109 into a chamber 110 containing a ball valve member 111, the latter being urged on to its seating by a spring 112. From below the seating of the ball valve member 111 a passage 113 leads into an annular working space 114 surrounding that part of the stem 96 which is exposed within the cylinder 21, while the passage 113 leads also to a lightly loaded

non-return valve 115 adapted to allow liquid from the space 114 to pass out to the fitting 16b and thus to the pipe line 16. The ball valve member 111 is capable of being opened against the spring 112 by a plunger member 116 adapted to slide in a liquid-tight manner within a bore formed in the end cap 23', said plunger member 116 having its lower surface acted upon by pressure liquid from the passage 103, i. e. the pressure liquid passing into the auxiliary working space 100. When the plunger member 116 is thus lifted a spigot 117 formed upon its upper part acts to raise the ball valve member 111 off its seating.

15 The trip valves 29 and 30 are connected by pipes 118 and 119 respectively with a fitting 120 containing a pair of non-return ball valve members 121 and 122, which are urged apart as shown by a coiled compression spring 123. The space 20 between said ball valve members 121 and 122 is connected by a fitting 38a with the shunt pipe line 38, as seen in Figure 1.

In order to ensure that the trip valves 29 and 30 are opened rapidly at the end of the stroke, a 25 resilient buffer device is incorporated in each of the pistons 24' and 25'. In the case of the piston 24' a hollow plunger member 124 having an air release hole 125 is mounted slidably within a bore 30 formed in the piston and is urged outwardly by a coiled compression spring 126 so as to engage with an abutment ring 127. The plunger member 124 is arranged to press upon the pin 32 as the piston 24' nears the end of its stroke, but the trip valve 29 does not open immediately, as it is 35 held closed by the spring 31 and by the supply pressure acting upon the said trip valve 29. As a consequence the plunger member 124 slides within the piston 24' and stores energy in the spring 126 until the force exerted by the latter is able to 40 push the trip valve 29 off its seating. The pressure liquid from the pipe 104 immediately surrounds the member 29, with the result that said member rapidly assumes its fully opened position, as the spring 126 is easily able to overcome the 45 spring 31. The trip valve 30 is arranged eccentrically on account of the stem 96 and therefore an annular plate 128 is provided upon the piston 25' for the purpose of actuating the pin 33. The plate 128 is mounted on headed pins 129 and is 50 urged away from the piston 25' by a coiled compression spring 130. The plate 128 acts, of course, in a manner exactly similar to that of the plunger member 124.

The power stroke of the pistons 24' and 25' 55 takes place in a direction towards the right and is effected by admitting pressure liquid into the fitting 15b so that said liquid flows through the pipe 105 and enters the working space 17. During this movement liquid is rejected from the auxiliary working space 100 and passes through the passageway 103 back to the prevailing return pipe line 16, while liquid filling the annular working space 114 is also able to return to the pipe line 16 by opening the non-return valve 115. It will be 60 seen that pressure liquid is unable to flow up the passageway 107 during this stage of the operation, as the ball valve 111 is closed. As the piston 25' nears the end of its stroke the plate 128 contacts with the pin 33 and eventually opens the trip valve 30, thus permitting the pressure liquid 65 from the fitting 15b to flow through the pipe 118 and into the shunt pipe line 38 by opening the non-return valve 122. This, of course, causes the reversing valve device 13 to change over, thus transposing the pressure liquid supply and 70 75

return pipe lines so that they become connected with the fittings 16b and 15b respectively. Pressure liquid then flows through the passage 103 and into the auxiliary working space 100 so as to effect the return stroke of the pistons 24' and 25'. The effective cross-sectional area of the auxiliary working space 100 is equal to that of a circle having the same outside diameter as the stem 96, and it will be seen, therefore, that with pressure liquid supplied at a given rate the pistons 24' and 25' will move towards the left at a relatively rapid speed. During this movement liquid is rejected from the working space 17 and part of this liquid is accommodated within the enlarging annular space 114 at the opposite end of the unit. It is for this purpose that the plunger member 116 is provided, the incoming pressure liquid acting beneath said plunger member so that it raises the ball valve member 111 off its seating, thus permitting the rejected liquid from the pipe 105 to flow through the passage 107, open the ball valve 108, and gain access to the annular space 114 by way of the ball valve 111 and the passage 113. The ball valve 108 may be omitted if desired, but its use is found to be beneficial, as it tends to steady the action of the ball valve member 111 and prevent the latter from hunting. As the end of this return stroke is reached, the trip valve 29 is opened by the plunger member 124, thus permitting pressure liquid to flow from the pipe 104 into the pipe 119 and the shunt pipe line 33 by way of the non-return valve 121 and once again changing over the reversing valve device 13 so as to cause the next power stroke to commence.

Figures 3, 4, 5 and 6 show the general arrangement and construction of a soot blower device incorporating the invention, the blower nozzle being of the retractable type adapted to be projected into the boiler furnace or the like during one stroke of the piston and cylinder unit and to be retracted back into its housing during the next stroke of said unit. The soot blower nozzle, which is not shown in the drawings but which can be of the usual construction, is attached to a nozzle shaft indicated at 140, the latter being caused to advance axially as it is rotated in one direction and to be retracted when it is rotated in the opposite direction. For this purpose a sleeve 141 having a screw thread 142 of coarse pitch formed on its exterior is securely attached to the tail portion 143 of the nozzle shaft 140 by means of a nut 144 and key 145. The sleeve 141 is protected by a cylindrical casing 146 forming part of a main casing indicated generally at 147, which latter is formed with a bearing bush 148 for the reception of a tubular spindle 149 formed integrally with a gear wheel 150. The spindle 149 is splined, as indicated at 151, these splines being slidable within longitudinal grooves 152 formed in the upstanding parts of the screw thread 142. Thus the sleeve 141 is capable of being rotated by the gear wheel 150, but is at the same time free to move in an axial direction. The main casing 147 carries a fixed nut member 153, which mates with the screw thread 142 and thus brings about the axial movement of the sleeve 141 and nozzle shaft 140 as these parts are rotated, thus of course advancing the blower nozzle into the boiler furnace during rotation of the shaft 140 in one direction and retracting it by rotation in the other direction.

The gear wheel 150 is in mesh with a larger gear wheel 154 formed integrally with a shaft 155 housed in bearings 156 and 157 upon the

main casing 147. If necessary the gear wheel 154 can be rotated by hand through the medium of a shaft 158 having a pinion 159 in permanent mesh with said gear wheel 154. During normal operation, however, the soot blower is worked by a double-acting liquid pressure unit which is indicated generally at 19 and which is shown diagrammatically in Figure 4 to indicate its relation to the cut-off and trip valve devices which will be hereinafter described. The unit 19 comprises briefly a cylinder assembly 161 which is closed at its two ends 162 and 163 and has pistons 164 and 165 slidable in its end parts. These pistons are connected together by a bar 166, which is formed upon its surface with rack teeth 167 to engage with corresponding pinion teeth 168 formed upon a transverse shaft 168. Thus as the pistons 164 and 165 are caused to reciprocate by pressure liquid the transverse shaft 168 correspondingly rotates first in one direction and then in the opposite direction. This reciprocation of the pistons is controlled by trip valve means which will be hereinafter described. The bar 166 is supported against deflection by engagement with a roller 170 (see Figure 3) mounted upon a pivot pin 171 which is carried firmly by the cylinder assembly 161. The transverse shaft 168 is mounted in bearings 172 and 173 formed in the centre part of the cylinder assembly 161, which latter has a frusto-conical flange portion 174 secured to the main casing 147 through the medium of a ring 175 composed of heat insulating material, thus to a large extent preventing the conduction of heat from the nozzle shaft 140 to the unit 160.

The transverse shaft 168 is drilled axially at 176 for the slidable reception of a push rod 177 adapted at one end to bear against a thrust member 178 fitted, also slidably, within an oblique bore 179 formed in the end part of the transverse shaft 168. The ends of the thrust member are rounded and in normal operation the outer of these ends, indicated at 180, projects beyond the corresponding end surface 182 of the transverse shaft 168 and engages with a recess 181 formed eccentrically in the adjacent end surface 183 of the shaft 155. These adjacent parts of the two shafts 168 and 155 are also formed off centre with coaxial bores respectively 40 for the accommodation of a dowel 186 serving to transmit torque from the shaft 168 to the shaft 155. The dowel 186 is so designed with regard to its material, its cross section, and its distance from the axis of the shafts 155 and 168 that it is just capable of transmitting the maximum torque that it is desired to impart to the gear wheel 154, so that if this torque is exceeded the dowel 186 will shear. It will be realised, of course, that it may be desirable, or even necessary in some cases, to provide two or more dowels such as 186 in order to carry the predetermined load.

The unit 160 is fed with pressure liquid through the pair of pipe lines 15 and 16, and connections 187 and 188 (see Figure 4), either one of which can supply the pressure liquid, while the other takes the rejected liquid, depending upon the direction in which the pistons 164 and 165 are being moved. The pipe line 188 does not lead directly to the unit 19, however, but is connected with a cut-off valve device indicated generally at 189, while a pipe 188a leads from the outer connection 190 of the valve device to the appropriate end of the unit 19. The cut-off valve device is shown more fully in Figure 3

and comprises a body 191 having a longitudinal bore 192 formed with a seating 193 for engagement by a spherical valve member 194. A plunger member 195 is slidable within the bore 192 and is urged by a strong spring 196 so as to hold the valve member 194 in its closed position, the spring 196 being of such strength that liquid within the pipe 188a and at a maximum pressure that is likely to be present in the remote control system as a whole is unable to force the valve member 194 off its seating. The plunger 195 is formed with holes 197, which enable the liquid to flow through said plunger when the valve device is open.

The cut-off valve device 189 is normally held in this open position, as shown in Figure 3, by a tappet 198 formed at its lower end with a pin 199 around which the liquid can flow in passing to and from the connection 190, a packing washer 200 being provided to prevent leakage of said liquid. At its upper end the tappet 198 is engaged by a roller 201 mounted pivotally upon a pin 202 extending between a pair of parallel twin link members 203 and 204. These are connected together by a bridge piece 205 and, at their upper ends, are mounted upon a pivot 206 carried by a casing 207. A lateral projection 208 formed upon the link 203, 204 engages an adjustable stop 209, and is maintained in this position by a spring 210 which acts upon a thrust member 211 extending between the link members 203 and 204 and pivoted thereto. The end of the thrust member 211 is disposed adjacent an adjustable screw 214 fitted in the end of the push rod 177. It will thus be seen that during normal operation of the soot blower the shaft 155 rotates as one with the transverse spindle 168, with the result that the push rod 177 remains in its retracted position, as shown in Figure 3.

If the soot blower becomes jammed for any reason, however, the driving force produced by the unit 19 is sufficient to shear the dowel 186 and the subsequent angular movement of the transverse spindle 168 relative to the shaft 155 causes the push rod 177 to deflect the link 203, 204, thus enabling the spring 196 to close the valve member 194. The cut-off valve device 189 is thus closed and it immediately prevents further operation of the unit 19; it will be seen that if pressure liquid happened at the time to be being fed through the pipe line 188 the flow would automatically be stopped by the ball 194 acting in the capacity of a non-return valve member. On the other hand, if the unit 19 were being driven in the opposite direction by pressure liquid passing through the pipe line 187 the closed valve ball member 194 would act to prevent the rejected liquid from escaping through the pipe 188a and thus no further pressure liquid would be able to enter the unit 19. The fact that the cut-off valve device is brought into action usually means that the blower device needs dismantling and overhauling, and in these circumstances it is of course easy to renew the dowel or dowels 186 and to re-set the cut-off valve device to its operative position. Means may, however, be provided if desired whereby the cut-off valve device 189 may be restored without the necessity of dismantling it. For example, a push button might be fitted in the casing 207.

The trip valve devices for the soot blower shown in Figures 3 to 6 are arranged so that when the feed of pressure liquid to the soot blower commences the nozzle shaft 140 is projected to the full extent into the boiler or like furnace, rotation

of said nozzle shaft in one direction taking place in the meantime. The following retracting stroke then commences, but terminates prematurely, the direction of movement of the nozzle shaft being reversed, while the nozzle itself is still disposed within the furnace space. The nozzle shaft, upon reaching its fully projected position, is once again reversed and executes a short stroke, and when it once again reaches its fully projected position a complete return stroke takes place, thus bringing the nozzle shaft back to its fully retracted position.

The mechanism to produce this effect is disposed within a casing 215, which contains a cam drum 216 mounted upon pivots 217 and 218 and formed in one with a gear wheel 219, which meshes with a pinion 220 fastened to the transverse shaft 163. The cam drum 216 is formed in its curved outer surface with a cam groove, which is indicated generally at 221 in Figure 3 and is arranged to be in permanent engagement with a follower pin 222 carried at the extremity of a follower arm 223, as will be seen in Figure 4. The arm 223 at its lower end is pivotally mounted upon a pin 224 carried by a block 225, which is itself mounted pivotally between a pair of arms 226 by means of a pin 227, the two pins 224 and 227 being disposed mutually at right angles so as to allow the arm 223 to have a universal movement. The arm 223 is urged towards the cam drum 216 by a pivoted leaf spring 228 and is arranged so that whenever the follower pin 222 is engaged by an end wall of the cam groove 221 said arm 223 is either lifted or depressed, depending upon the direction in which the cam drum 216 happens to be rotating. Such lifting or depressing movement is imparted to the arms 226, which are formed in one with a tubular member 229 mounted between pivots 230 and 231 (see Figure 3). The tubular member 229 is also formed with a pair of upwardly extending arms 232 carrying between them a roller 233, which is adapted to open either the trip valve member 29 or the trip valve member 30, depending upon whether the follower arm 223 is depressed or lifted respectively.

The mechanism for operating the trip valves 29 and 30 is the same in each instance, and only that corresponding to the trip valve 30 has been shown in detail in Figure 4. It comprises a slider 234 which moves within a tubular fitting 235 and is fitted with an adjustable screw 236 adapted to be engaged by the roller 233. A plunger member 124 is urged towards an abutment ring 127 by means of a coiled compression spring 126 and is adapted to engage the end of a pin 32 when the slider 234 is urged towards the left. When sufficient force has been built up in the spring 126 the trip valve is operated in a manner exactly similar to that of the trip valve 29 shown in Figure 2. When the trip valve 30 opens, pressure liquid from the pipe line 15 is able to flow past a spring-loaded non-return valve 35 and thus enter the shunt pipe line 38 by way of a pipe connection 37. In a similar way a non-return valve 34 is associated with the trip valve 29 and leads by a passage 36 into the shunt pipe line 38.

Figure 5 is a flat development of the curved surface of the cam drum 216, and it will be seen that the cam groove 221 follows a tortuous path in order to produce the above-mentioned sequence in the movements of the nozzle shaft 140. When the nozzle shaft 140 is in its completely retracted position, the drum 216 is so disposed that the follower pin 222 occupies the position shown in

dotted lines at the extremity of a terminal portion 237 of the groove 221. It will be appreciated that in practice the drum rotates while the pin 222 remains substantially fixed, but in order to simplify this description the pin 222 will be regarded as moving along the groove 221. Where "junctions" occur in the groove 221 the latter is shaped specially in order that the pin 222 may follow a uni-directional course, and an example is shown in perspective in Figure 6, which corresponds to the junction 238 occurring at the lower part of the terminal portion 237. The pin 222, in moving downwards, is required to pass into the oblique portion 239, and therefore the "branch" groove 240 has its bottom arranged to slope upwards as indicated at 241, a triangular "flat" portion 242 being provided so as to produce a relatively low wall 243 for the groove 237 where the latter is met by the branch groove 240. This, of course, efficiently guides the follower pin 222 past the branch groove 240, but later in the cycle of operations enables said pin, in travelling along the branch groove 240, to rise up the sloping bottom 241 and subsequently move back into the terminal portion 237. Other sloping portions similar to 241 are provided at various positions in the groove 221 and are indicated at 244, 245, 246, 247 and 248.

When pressure liquid is first fed to the soot blower the extending movement of the nozzle shaft 140 is accompanied by downward movement of the pin 222 relative to the surface of the drum 216, said pin passing along the oblique portion 239 of the groove, riding up the sloping portion 244, and then dropping into a terminal portion 249 along which the pin travels until it reaches the end 250. The rotation of the drum 216 causes the pin 222 to be raised, thus opening the trip valve 39 and reversing the direction of the nozzle shaft 140 and also said drum 216. The pin 222 therefore returns along the terminal portion 249, but is diverted by the low wall of the groove at 251 and thus rides up the sloping bottom 245, said pin 222 shortly reaching another terminal portion at 252. This, of course, reverses the movement of the nozzle shaft 140 before the nozzle itself has been withdrawn from the boiler or like furnace and causes said nozzle shaft 140 to move forward once again, the pin 222 travelling along a portion 253 of the cam groove and eventually riding up a sloping bottom at 246. The pin 222 soon reaches the next terminal portion indicated at 254, which brings about another short retracting stroke, said pin 222 travelling along a portion 255 of the groove and eventually reaching a terminal portion 256. Reversal occurs once again and the pin 222 returns along the portion 255 until it is deflected sideways by the low wall of the groove at 257, said pin subsequently rising up the sloping bottom 248 and bringing about another reversal as it reaches a terminal portion 258. This begins the final retracting stroke of the nozzle shaft 140 and the pin 222 passes along a portion 259 of the groove until it rides up the sloping bottom 241, thus re-entering the terminal portion 237 and reaching the end position indicated at 260. If the supply of pressure liquid is maintained another reversal occurs and the cycle recommences.

It will, of course, be appreciated that various other forms of trip valve device may be arranged in accordance with the invention and that the construction of the reversing valve device may be modified as desired. The invention is, of course, not restricted to soot blowers, as it is ap-

plicable to many forms of liquid pressure remote control systems.

What I claim is:

1. A liquid pressure remote control system comprising, a double acting piston and cylinder unit consisting of a hollow piston open at one end, the closed end of said piston and the cylinder together defining a major working space, a tubular stem fixed to one end of the cylinder and adapted to extend into the open end of the piston, packing for effecting a liquid-tight seal between the stem and the interior of the piston, means for bypassing a portion of the liquid ejected from the major working space into the annular space defined by the tube and the walls of the cylinder during reduction of the cubic area of said major working space, a source of liquid under pressure, a reversing valve, supply and return conduits connecting said reversing valve and said source of liquid under pressure, said valve including two ports, means connecting one of said ports to the tubular member of the piston and cylinder unit, means connecting the other of said ports to the major working space of said piston and cylinder unit, said reversing valve also including a movable portion adapted in one position to discharge liquid under pressure through one of the ports and to receive it through the other and in the other position to reverse the direction of flow through each port, and means responsive to a predetermined relative movement of the piston and cylinder unit in either direction for changing the position of the movable portion of said reversing valve to cause reversal of flow through the ports thereof, whereby alternate sides of the piston and cylinder unit will be alternately supplied with liquid under pressure causing reversal of direction at the completion of each stroke.
2. A liquid pressure remote control system comprising, a double acting piston and cylinder unit consisting of a hollow piston open at one end, the closed end of said piston and the cylinder together defining a major working space, a tubular stem fixed to one end of the cylinder and adapted to extend into the open end of the piston, packing for effecting a liquid-tight seal between the stem and the interior of the piston, said interior constituting a minor working space, a source of liquid under pressure, a reversing valve, supply and return conduits connecting said reversing valve and said source of liquid under pressure, said reversing valve including two ports, a conduit connecting one of said ports with the minor working space of said piston and cylinder unit, another conduit connecting the other port to the major working space of said piston and cylinder unit, said valve including a movable portion adapted in one position to discharge liquid under pressure through one of the ports and to receive it through the other, and in the other position to reverse the direction of flow through each port, a valve normally spring closed located at either end of said piston and cylinder unit, each valve including a pin extending into the respective working space, a member carried at each end of said piston to engage the respective valve pin to open the respective valve, said members being spaced from the respective ends of the piston by springs capable of storing energy, one of said valves being adapted to be opened by a member carried at the end of a piston engaging a pin upon completion of its stroke in either direction, an auxiliary hydraulic motor for changing the position of the movable portion of

said reversing valve to cause reversal of flow through the ports thereof, and a conduit connecting said auxiliary motor with each of the conduits connecting said ports and the working spaces of said piston and cylinder unit, the conduit connecting the auxiliary motor with the conduit serving one working space leading through the valve contiguous to the other working space, whereby the opening of a valve at the completion of the stroke of the piston will divert the pressure liquid being fed to the opposite side thereof to the auxiliary motor to effect reversal of flow through the ports.

3. A liquid pressure remote control system comprising, a double acting piston and cylinder unit consisting of relatively movable elements, a source of liquid under pressure, a double acting hydraulic motor, means including a single movable valve element for selectively connecting said source of liquid under pressure and one of the opposite sides of said piston and cylinder unit and for simultaneously selectively connecting one of the opposite sides of said motor, valves normally closing both of the connections established by said means between said source of liquid under pressure and said motor, means responsive to relative movement of predetermined magnitude on the part of the elements of said piston and cylinder unit for opening one of said valves to open the connection between said pressure liquid and said motor to cause operation of the latter, and a mechanical linkage operatively connecting said motor to the movable valve element to move the latter to another position to connect the other side of the piston and cylinder unit and the other side of the motor with said source of liquid under pressure, whereby upon predetermined relative movement of the elements of the piston and cylinder unit in one direction a normally closed valve will be opened to actuate the motor to move the movable valve element to a position causing reversal of the direction of relative movement of the elements of the piston and cylinder unit.

4. A liquid pressure remote control system comprising, a double acting piston and cylinder unit, a source of liquid under pressure, a reversing valve including a portion movable into either of two positions, supply and return conduits connecting said reversing valve and said source of liquid under pressure, a liquid pressure piston and cylinder motor, a mechanical linkage connecting a moving portion of said motor with the movable portion of said reversing valve, said reversing valve including four ports, conduits connecting two of the ports with opposite sides of the piston and cylinder unit, conduits connecting the other two ports with opposite sides of the motor unit, branch conduits leading from each of the conduits connecting the reversing valve with opposite sides of the piston and cylinder unit, a normally closed check valve in each of the branch conduits, a common conduit connecting each of said branch conduits on the normally closed side of the check valve with the reversing valve, said reversing valve in one position of its movable portion establishing connections between said source of liquid pressure and one side of the piston and cylinder unit and between said common conduit and one of the conduits connecting the reversing valve and one side of the motor and in the other position of its movable portion establishing connections between said source of liquid under pressure and the other side of said piston and cylinder unit and between

5 said common conduit and the other conduit connecting the reversing valve and the motor, and means responsive to a predetermined relative movement of the elements of said piston and cylinder unit in either direction for selectively opening one of said normally closed valves to establish a connection between said source of liquid under pressure and one side of said motor to actuate the same to cause movement of the movable portion of the reversing valve to its other position thereby to cause reversal of the movable portion of the piston and cylinder unit.

10 5. A liquid pressure remote control system as claimed in claim 4 further comprising, a spring coating with the linkage connecting the movable portion of the valve and a movable portion of the motor to shift both of said movable portions rapidly from one extreme position to the other upon completion of a portion of the stroke 20 of the auxiliary motor, whereby a time lag is eliminated.

15 6. A liquid pressure remote control system as claimed in claim 4 in which the mechanical linkage connecting the movable portion of the reversing valve and the movable portion of the auxiliary piston and cylinder unit comprises, a pivoted arm connected to the movable portion of said reversing valve and to the movable portion of said auxiliary motor, each of said connections being of the lost motion type, said arm being provided with a spring arranged to pass a dead center position and thereby to rapidly shift the movable portion of said reversing valve from one position to the other as the movable portion of the auxiliary motor executes its stroke.

25 7. A liquid pressure remote control system as claimed in claim 4 in which the mechanical linkage connecting the movable portion of the reversing valve and the movable portion of the auxiliary piston and cylinder unit comprises, a pivoted arm connected to the movable portion of said reversing valve and to the movable portion of said auxiliary motor, each of said connections being of the lost motion type, said arm being provided with a spring arranged to pass a dead center position and thereby to rapidly shift the movable portion of said reversing valve from one position to the other as the movable portion of the auxiliary motor executes its stroke, the free 30 angular movement of said arm to take up the lost motion in the connection to the movable portion of the reversing valve being greater than the free angular movement of said arm to take up the lost motion in the connection to the movable portion of said auxiliary motor.

35 8. A liquid pressure remote control system comprising, a double acting piston and cylinder unit, a reversing valve controlling the working space of the unit to which liquid is supplied, a double acting auxiliary hydraulic motor for actuating said reversing valve, trip valves controlling the flow of liquid to said auxiliary motor, cam means driven by the movable portion of the piston and cylinder unit, and means driven by 40 said cam for actuating said trip valves, said cam being provided with grooves for the reception of a portion of the cam operated means, said grooves being arranged in a circuit, the line of development of said cam being a function of the time of actuation of said trip valves, whereby the amplitude of the stroke of the piston and cylinder unit may be automatically varied under the control of a cam driven thereby.
